(57) **CLAIM**

The ornamental design for a game controller stand, as shown and described.

DESCRIPTION

FIG. 1 is a front, right and top perspective view of a game controller stand, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines immediately adjacent to the shaded surfaces depict the bounds of the claimed design, whereas all other broken lines shown in the drawings illustrate portions of the game controller stand that form no part of the claimed design.
